(57) **CLAIM**

The ornamental design for a dental implant with internal passageway, as shown and described.

DESCRIPTION

FIG. 1 is a perspective view of a dental implant with internal passageway showing my new design;

FIG. 2 is a front elevation thereof shown on a slightly reduced scale, the side opposite being a mirror image;

FIG. 3 is a right side elevation thereof the side opposite being a mirror image;

FIG. 4 is a top plan view thereof; and,

FIG. 5 is a bottom plan view thereof.
